DISPENSER OR THE LIKE

Michael J. Fomusa and Peter W. Fomusa, Chicago, Ill.; said Michael J. Fomusa assignor to Nathan Fomusa, Chicago, Ill.

Application July 23, 1948, Serial No. 147,738

Term of patent 14 years

(Cl. D4—3)

To all whom it may concern:

Be it known that we, Michael J. Fomusa, a citizen of the United States, residing at Chicago, in the county of Cook and State of Illinois, and Peter W. Fomusa, a citizen of the United States, residing at Chicago, in the county of Cook and State of Illinois, have invented a new, original, and ornamental Design for a Dispenser or the like, of which the following is a specification, reference being had to the accompanying drawing, forming part thereof.

In the drawing:

We claim:

The ornamental design for a dispenser or the like, as shown.

MICHAEL J. FOMUSA.
PETER W. FOMUSA.
